UNITED STATES PATENT OFFICE.

JOHN W. NELSON, OF VIOLA, KANSAS.

SANITARY CLOSET.

1,121,530.

Specification of Letters Patent. Patented Dec. 15, 1914.

Application filed July 23, 1914. Serial No. 852,735.

To all whom it may concern:

Be it known that I, JOHN W. NELSON, a citizen of the United States, residing at Viola, in the county of Sedgwick and State of Kansas, have invented certain new and useful Improvements in Sanitary Closets; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in sanitary closets especially adapted for use where it is not convenient for connection with a sewerage system, and comprises a simple and efficient apparatus of this nature having various details of construction, and arrangement of parts as will be hereinafter more fully described and then specifically defined in the appended claim.

My invention is illustrated in the accompanying drawings which, with the letters of reference marked thereon form a part of this application and in which,

Figure 1 is a central vertical sectional view through the apparatus, Fig. 2 is a similar view in vertical section taken in a plane at right angles to the showing in Fig. 1, Fig. 3 is a central vertical section through the receptacle and closure, and Fig. 4 is a perspective view of the receptacle.

Reference now being had to the details of the drawings by letter, A designates a box having a door B hinged to the marginal edge of a side opening therein, and C is an opening in the seat D, the latter being raised a slight distance above the top in order that the flanged cover E may fit down tightly thereover. A hook E' is fastened to the outer surface of the box, and is designed to be engaged by the toggle latch F, which is pivoted intermediate its ends to the bail shaped member F', which in turn is pivoted to the plate F² fixed to the cover, the latter being hinged to the rear wall of the box. The end of the latch is designed to engage the hook, and when the latch is given a swinging movement upon its pivotal bail, the latch will buckle and cause the seat to be held tightly to the top of the box and over

the seat forming a sealed joint and thereby preventing the escape of noxious odors from the receptacle G. A suitable hopper I is secured to the under surface of the seat, and which telescopes within the opening in the top of the receptacle. The bottom of the receptacle is provided with an exit opening, which is closed, when the receptacle is in use, by means of the closure J, hinged to the bottom of the receptacle, and having a bail shaped member L, pivoted to one edge thereof, and which latter in turn has a pivotal fulcrum latch lever O mounted thereon, one end of which is adapted to engage a hook N on the side of the receptacle, and forming means, whereby as the end of the latch lever is fulcrumed in the hook N, and the lever latch swung up against the side of the receptacle, the closure may be drawn tightly to its seat, and form a hermetically closed exit.

The upper portion of the receptacle is provided with suitable handles M, and a cover M' with a handle thereon, and which may be inserted in the opening in the top of the receptacle when the latter is removed from the box, and form a hermetically sealed closure. Hooks Q are fastened to the opposite sides of the receptacle near its upper end, and under which fulcrum levers R may engage, and which, when brought into engagement with the hooks S depending from the under surface of the top of the box, will serve to hold the receptacle in place under the hopper, to receive excrement.

By the provision of an apparatus embodying the features of my invention, it will be noted a simple and efficient means is provided, which will be thoroughly sanitary, and which may be conveniently used where sewage systems are not to be had to receive and take care of the sewage.

What I claim to be new is,—

A sanitary closet, comprising a box with an opening in the top thereof, bracket irons secured to the undersurface of the top, a receptacle within the box and provided with a top having an opening therein with a beveled wall, a flanged tapering hopper extending through the opening in the top of the box and the opening in the receptacle, the tapering wall of the hopper engaging the beveled wall of the opening in the receptacle, a seat holding the flange of the hopper

against the upper surface of the top of the box, hooks upon the receptacle, links pivoted to said bracket irons, and fulcrum levers pivotally mounted upon said links and designed to suspend the receptacle and hold the latter snugly against the tapering wall of the hopper, as set forth.

Copies of this patent may be obtained for five cents each, by addressing the "Commissioner of Patents, Washington, D. C."

In testimony whereof I hereunto affix my signature in presence of two witnesses.

JOHN W. NELSON.
